UNITED STATES PATENT OFFICE.

LLOYD T. REMICK, OF BROCKTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR FINISHING THE EDGES OF FLEXIBLE MATERIAL.

1,310,579.

Specification of Letters Patent. Patented July 22, 1919.

Application filed April 13, 1914. Serial No. 831,614.

To all whom it may concern:

Be it known that I, LLOYD T. REMICK, a citizen of the United States, residing at Brockton, in the county of Plymouth and State of Massachusetts, have invented certain Improvements in Machines for Finishing the Edges of Flexible Material, of which the following description, in connection with the accompanying drawings, is a specification, like reference characters on the drawings indicating like parts in the several figures.

This invention relates to the manufacture of boots and shoes and is herein illustrated in connection with a machine for folding the margin of a piece of flexible material and for guiding into or adjacent to the fold a flexible filament, which in the illustrative embodiment of the invention is a reinforcing element.

In the preparation of shoe uppers certain exposed edges as, for example, those of the top of the upper and along the throat or fly, must be finished to present a smooth, attractive appearance. This is usually done by skiving the edge, applying cement thereto, and folding over the margin upon the cemented portion. The uppers may then, if desired, be stitched through the folded portion as a further securing means and for the purpose of ornamentation. A large proportion of all the folding was usually performed by hand, but since the advent of machines of the type disclosed in the Patent to Glass No. 1,281,555, this work has been very satisfactorily performed by such machines. For convenience the present invention will be described in connection with a machine of this type.

One object of the present invention is to produce a finished edge which will not be liable to stretch, or to produce an edge for any purpose where additional strength along the margin of the sheet material to be finished is required.

It has been found for instance that, in certain classes of shoes, for example, in oxfords having uppers of rather firm leather, the usual fabric lining of the upper may be dis-

pensed with provided the free margin of 50 the upper which is subjected to the folding operation above described is suitably reinforced to prevent stretching. Any suitable form of reinforcing means may be used, as for instance, a cotton or linen cord or tape 55 which may be applied in position adjacent to the folded-over margin of the upper either before or in conjunction with the folding operation. For example it has been found that a cord introduced into the crease of the 60 upper prior to the folding of the margin down upon the body of the work and extending in the crease substantially around the folded portion of the upper serves to provide the necessary firmness and strength usually secured by a fabric lining extending over the entire interior of the shoe upper.

According to one feature of the invention, a flexible filament, which may have a reinforcing function, is conducted to a position 70 adjacent to the margin, and a hammer afterward presses both a portion of the folded margin and a portion of the filament upon the body portion of the work.

In the use of the illustrative machine the 75 filament is a reinforcing cord which is guided into the crease of the fold and is pressed between the folded over margin and the body of the work; but the invention is not so limited, and it is intended to claim 80 broadly the proper laying of the filament irrespective of its function either in or adjacent to the fold.

Further features of the invention relate to the combination with mechanism for guiding the filament, of means for slitting the margin of the work when desired and to a construction and arrangement of parts which facilitate the proper laying of the filament upon pieces of work the edges of which 90 have sharply curved localities.

It is to be understood that the member referred to above as a cord or reinforcing element may, within the invention, be a thread, tape, band, string or other suitable member 95 which for the purpose of this application may be designated by the general term filament or filamentous element.

These and other features of the invention will be described in connection with an illustrative machine and pointed out in the appended claims.

5 Referring to the accompanying drawings—

Figure 1 is a perspective view of the work table of a machine with its overhanging arm and the folding instrumentalities and means 10 for introducing the reinforcing element;

Fig. 2 is an enlarged view of the creaser and cord guiding means;

Fig. 3 is a detail in perspective of the folding and cord inserting instrumentalities 15 ties operating upon a piece of stock;

Fig. 4 is a perspective view of the folding and cord introducing instrumentalities, the latter being modified;

Fig. 5 is a view similar to Fig. 3 of the 20 modified form of cord introducing means;

Fig. 6 is a detail of the modified form of the creaser;

Fig. 7 shows the step of cementing the margin of the material;

25 Fig. 8 is a view of a shoe upper illustrating the work performed by the machine.

The instrumentalities which operate to fold the margin of the sheet material in the treatment of which this invention is to be 30 practised may be substantially those shown and described in the patent above referred to, and for the purpose of illustration such instrumentalities are herein shown, for a full description of which reference may be 35 had to the said patent, it being sufficient herein to refer to their operation and to include only in a general way a description of their construction and the means whereby they are actuated.

40 In Fig. 1 is shown in perspective a view of the work table 2 of the machine and the overhanging arm 4 upon the left hand end of which certain of the operating instrumentalities are mounted.

45 For the purpose of description it will be convenient to regard the arm 4 as extending in a general direction from the right to the left side of the machine and a line at right angles to this as extending from 50 front to rear of the machine, the operator's position being in front of the machine, that is, in the position toward which the forwardly turned left-hand end of the arm 4 points.

55 As the portion of sheet material to be operated upon is presented to the machine the edge is pushed toward the right into engagement with the upwardly curved surface of a plow 10 which turns the edge upwardly until it encounters an overhanging end 11 of the plow or until it engages the pivoted gage 12 which may be adjusted somewhat below the projection 11. The portion 11 of the plow 10 or the pivoted gage 12 determines 60 the distance the material can be inserted

and hence determines the width of the fold. The gage 12 may be adjusted by a screw 14 to vary to some degree the width of the fold. If a greater variation in the width of the fold than can be secured by an adjustment of the pivoted gage 12 is desired, 70 the plow 10 may be removed and one of different shape inserted in its place.

In order to clamp the work during the formation of the fold in the margin of the 75 sheet, a yielding presser 20 is provided which is actuated upwardly at the proper time in the cycle of the machine to press the work against the under face of a creaser 22. The presser block 20 is actuated through 80 resilient means (not shown) to avoid applying excessive pressure to the work and to permit its retraction manually for the introduction and removal of the work.

The right-hand face of the creaser 22 85 which is best shown in Fig. 2 determines by its lower edge the line of fold and operates with a folding finger 24 which is actuated upwardly and at an inclination toward the left to fold the margin of the 90 upper across the lower edge of the face of the creaser, and to give to that edge a total bend of more than 90° relatively to the plane of the body of the sheet. The upward movement of the folding finger 24 to form 95 this fold or loop in the stock occurs while the stock is clamped between the presser block 20 and the lower face of the creaser 22 and before the stock is fed.

At this stage in the treatment of the material and in accordance with the present invention a reinforcing member is inserted into the fold which is being made by the machine. One form of mechanism by which the invention may be practised satisfactorily, is shown in Figs. 1, 2 and 3, which have already been partially described. The reinforcing member 30, which for convenience may be referred to as a cord, is brought from a spool or reel, not shown, through the 110 end 32 of a rod 34 adjustably supported in the collar 36 in which it is held by a set screw 38. The collar 36 is supported by a bracket 40 which is held on the table of the machine by a screw 42. From the end 32 115 of the rod 34 the cord is passed through a hole 44, Fig. 2, to the left-hand side of the rod and is then threaded through an opening 46 (Fig. 3) in a direction toward the operating instrumentalities in the machine 120 and emerges from an opening 48 in the rearwardly turned end of the rod 34 in position to be carried into the bight of the fold and across the right-hand face of the creaser or fold guide 22.

To insure that the cord will be properly placed in the angle formed in the upper and particularly to position it accurately in the bight of the fold, the lower edge of one of the active faces of the creaser for instance 130

the face 49 is provided with a groove 50 along which the cord moves as the work is fed.

The groove 50 is located as near as possible to the lower edge of the face 49 of the creaser so that the reinforcing member will be introduced into the bight of the fold and directly against the inner face of the upper material.

10 If a concave or inside curve of the material is being folded it is desirable to snip the marginal portion of the edge at this stage in the folding operation. For this purpose a snipping knife 56 is provided. The knife 56 is mounted on a lever 58 pivoted to the arm 4 at 60 and operated by a connection 62 by actuating means located below the table 2. The knife 56 coöperates with the advance edge 64, Fig. 1, of the plow 10 to make a 15 shearing cut through the marginal portion of the material in order that the fold may be formed properly around a concave curve of the material being treated, as shown at *a* in Fig. 8. For straight edges the snipping 20 knife is, usually, thrown out of operation.

To complete the folding of the margin of the sheet material down upon the body portion thereof to press the parts together and effect the setting of the cement and to pre- 30 sent a new portion of the material to the folding instrumentalities, there are provided the anvil block 70 and the hammer 72. The work supporting surface of the anvil block 70 is beveled obliquely downwardly toward 35 the yielding presser block 20, that is, toward the point where the fold is completed and also toward the right-hand side of the machine, that is, toward the line of direction of the feed of the work. This construction 40 of the anvil eliminates the tendency to stretch the edge of the work in the folding and plaiting operations. Since the rearmost portion of the portion of the margin being treated is held upright by the plow 10 and 45 by the folding finger and the advance portion of the margin is folded over upon the body of the work there is an objectionable tension or strain exerted upon the edge of the work between these two points. The in- 50 clined surface of the anvil and the correspondingly inclined surface of the hammer 72 which coöperates with it prevent undue stretching of the edge of the work due to the said tension or strain, since the folded portion of the work is held in an oblique position instead of being folded flat in the plane of the body portion of the work. Also where a convexly curved portion of the work is being treated the inclined surfaces of the anvil 55 and hammer facilitate the formation of transverse creases or plaits which are necessary to take care of the fullness of the edge and are shown at *b* in Fig. 8. This double obliquity of the anvil face toward the right 60 and toward the front, as described, has been

found particularly advantageous in eliminating the objectionable stretching of the edge, particularly in connection with the cord introducing mechanism.

At the time the fold is being completed by 70 the anvil 70 and the hammer 72, the anvil is located contiguous to the presser block 20 and the hammer 72 is actuated forwardly and downwardly to fold over a portion of the margin of the material and press it 75 firmly against the anvil block, the points of completion of the fold being at the forward edge of the anvil block. In order that this action may be effected without bending the margin of the work at a sharp angle the ad- 80 vance face of the creaser 22 is cut away at 74, (Figs. 2 and 3) to give space for the upper material and yet permit the hammer 72 to approach very closely the advance edge of the creaser. This grouping of the folding 85 instrumentalities in a short space longitudinally of the direction of feed enables the machine to operate with great facility around sharp curves which frequently occur in work upon shoe uppers.

90 After the fold has been firmly pressed between the hammer and the anvil the two are moved together a certain distance to effect the feed of the work. This distance is under 95 the control of the operator and may be varied during the operation of the machine, this control being desirable since it is practicable to employ a much longer feed stroke when folding a straight edge than when folding a curved edge.

100 In order to insure that the feed of the work shall take place when the stock is first inserted in the machine without the operator's taking care to advance the work far enough to insure that the hammer 72 will 105 engage it, a foot 76 is provided. The foot 76 is made of spring steel and is secured at 78 to the hammer 72. The foot 76 extends forwardly into a space formed by cutting away a portion of the creaser member in which 110 space the stock will be exposed when it is first inserted in the machine. The front end of the foot 76 is downturned at 80, Fig. 4, to form a toe which gets a firm grip on the material and insures a positive feed of the 115 work as the hammer moves rearwardly in the direction of feed.

A somewhat different form of the creaser and cord guiding mechanism is shown in Figs. 4, 5 and 6. In the machine as illustrated in these views, the rod 34 with its guide openings for the cord is dispensed with and in place thereof a hole 90 is bored through the creaser member in a direction toward the rear and inclined toward the 120 right. The hole is also inclined downwardly and emerges on the right-hand face of the creaser preferably, though not necessarily, at a point a short distance in front of its rear end, that is, its advance end with re- 125 130

lation to the direction of feed. From the hole 90 to the advance end of the creaser the groove 50 is preserved and serves as in the previously described construction to locate the reinforcing element in the bight of the fold formed by the folding mechanism.

Preferably a suitable tension device 82 is provided which may be mounted upon a bracket 84 secured to the head of the machine at 86. The cord is guided from a reel or spool through a guide 88 and through the tensioning device 82 to the opening 90 in the creaser 22 through which it is threaded.

15 the work may now be inserted and the operation of folding successive portions of the upper and inclosing the reinforcing element in the fold will proceed automatically. When one piece of work is finished, another 20 may be inserted without cutting the cord and when a run of work has been completed the cord connecting the pieces may be severed.

Although the flexible thread, tape, ribbon 25 or other member, which has been termed broadly a filament, has been shown and described as a reinforcing element, it should be understood that the particular nature and function of the flexible element is immaterial so far as the broader aspects of the 30 invention are concerned.

The method which has been disclosed above is not claimed herein but forms the subject-matter of a divisional application 35 Serial No. 866,673, filed October 14, 1914, which has resulted in Patent No. 1,226,117.

Having thus described the invention, what is claimed as new and desired to be secured by Letters Patent of the United States is:—

40 1. In an upper folding machine the combination of a folding finger, a coöperating creaser for determining the line of the fold, means for completing the fold, and means for introducing between the creaser and the 45 folded material a filament of reinforcing material.

50 2. A machine for folding the edge of sheet material comprising coöperating folding devices one of which is constructed and arranged to guide a flexible filament into the vertex of the fold.

55 3. In a machine for progressively folding over the margin of a piece of sheet material upon itself, the combination of means for turning up the edge of the sheet material to initiate the fold, means across which the upper is folded to determine the location of the crease, means for introducing into the crease a flexible filament of reinforcing material, and means for completing the folding 60 of the margin of the material down upon itself to inclose said filament and into position to be secured by cement.

65 4. A machine for folding the margin of sheet material, having in combination fold

forming means, means for introducing into the fold a flexible filament, a hammer and an anvil coöperating therewith to press down the folded over portion upon the body portion of the upper to inclose the flexible 70 filament.

5. In a machine for folding the margin of shoe material, the combination of means for forming the fold in a marginal portion of the material, means for slitting the edge 75 of the material during the fold forming operation, and means for inserting into the fold beyond the slit portion a flexible filament.

6. A machine for folding the margin of 80 shoe material having in combination means for initiating the fold in the margin of the material, means for slitting the edge in which the fold has been initiated, means for inserting into the partially formed fold a 85 reinforcing element, and means for completing the fold to inclose said element.

7. A machine for folding the margin of shoe material having in combination a fold guide or creaser mounted with its edge in 90 the line of feed of the material, a folding finger mounted for reciprocation across the edge of the fold guide to form a fold in the material, and means for guiding a reinforcing element along said edge between the 95 creaser and the folding finger.

8. A machine for folding the margin of shoe material having in combination a work support, a fold guide or creaser having an edge over which the material is adapted to 100 be bent partially to form a fold, a folding finger coöperating with said creaser, means for slitting the edge of the material, and means for introducing a reinforcing element into the fold as thus formed over the edge 105 of the creaser.

9. A machine for folding the margin of shoe material having in combination a work support, a fold guide or creaser located above the support, means for initiating the 110 fold in the margin of the upper, a folding finger coöperating with the creaser to continue the folding operation until the folded over portion makes an acute angle with the body portion of the material, means for introducing into said angle a reinforcing filament, and means for completing the folding of the upper over the reinforcing filament. 115

10. A machine for folding the margin of shoe material having in combination a work 120 support, a fold guide or creaser located above the support, means for initiating the fold in the margin of the upper, a folding finger coöperating with the creaser to continue the folding operation until the folded over portion makes an acute angle with the body 125 portion of the material, means for inserting into said angle a reinforcing filament, means for slitting the upper at an intermediate step in the folding operation, and means 130

for completing the folding of the upper over the reinforcing filament.

11. A machine for folding the margin of sheet material having in combination a work support, a fold guide or creaser located above the support, means for initiating the fold in the margin of the upper, a folding finger coöperating with the creaser to continue the folding operation until the folded over portion makes an acute angle with the body portion of the material, means for inserting into said angle a reinforcing filament, means acting to slit the edge of the material after the initiation of the fold and prior to the insertion of the reinforcing filament, and means for completing the folding of the upper over the reinforcing filament.

12. A machine for folding the margin of sheet material with convex curves on the edge thereof, having in combination a fold guide or creaser, a folding finger, means for reciprocating the finger transversely of the edge of the creaser to turn up the edge of the material at an angle to the body portion of the material, means for inserting a reinforcing filament between the creaser and the material, pressing means in advance of and adjacent to the creaser adapted to complete the folding of the material over the reinforcing filament and having its engaging faces at an inclination to the direction of the acting edge of the creaser to facilitate the formation of folds in the material when passing around convex curves of the edge.

13. In a machine of the class described the combination with mechanism adapted to fold the margin of shoe material having a concave edge, of means for introducing into the fold as thus formed a cord or filament, and slitting mechanism acting to slit the edge of the material during the formation of the fold and prior to the introduction of the cord into the fold.

14. A machine of the class described having in combination folding mechanism adapted to operate upon a concave edge, means for slitting the edge prior to the completion of the fold therein, and means for guiding a flexible filament into the fold formed by the folding means.

15. A machine of the class described having, in combination, means to feed a piece of sheet material intermittently into position to have its margin operated upon, means for progressively folding said edge comprising a creaser and a folding finger coöperating with the creaser to bend the margin of the material about the edge of the creaser, and means for introducing between the creaser and the finger a reinforcing element.

16. In a machine for folding pliable material, the combination of a bed, a work table and folding finger, feeding means, and a creaser overlying the work and underlying

the edge folded by the folding finger, said creaser being provided with guiding means whereby a reinforcing element may be guided into the fold formed by the creaser and the folding finger and into position to be fed by said feeding means.

17. A machine of the class described having, in combination, means for feeding a piece of material intermittently into position to have its margin operated upon, means for progressively slitting and folding said margin, said last-named means including a creaser about which the edge of the fold is made, and means for introducing into the fold a flexible filament.

18. A machine of the class described having, in combination, means for feeding a piece of material intermittently into position to have its margin operated upon, means for progressively folding said margin, said last-named means including a folder and a creaser across the edge of which the folder acts, and means for guiding across an active face of the creaser and into the fold formed by said folding means a reinforcing cement.

19. A step-by-step folding machine having, in combination, a cutter for slitting the margin of a piece of material, a folding finger located at one side of and adjacent to the cutter, a presser located at one side of and adjacent to the folding finger, a creaser about which the slitted margin is bent by the folding finger, means for guiding into the angle of the fold formed by the creaser and folding finger a flexible filament, means for actuating the presser to complete the fold and feed the work including the flexible filament, and means for actuating the cutter and the folding finger to do their work.

20. A machine of the class described having, in combination, means for feeding a piece of material intermittently into position to have its margin operated upon, a creaser and a folder past which the material is fed, means constructed and arranged to introduce in fixed relation to the edge of the material a reinforcing element, means for causing relative movement between the folder and the creaser to form a fold over said reinforcing element, and means for pressing the folded portion upon said element and upon the body of the piece of material.

21. A folding machine for doubling the edge of sheet material in a series of steps comprising a support for the stock, a fold guide or creaser arranged to bear on the surface of stock lying on said support, a turning device movable across the line of fold established by said creaser, means for introducing along the line of fold a reinforcing element, and means for feeding the stock step by step in the direction of the line of feed.

22. A machine of the class described having, in combination, means for feeding a piece of material intermittently into position to have its margin operated upon, and 5 means for progressively folding the margin, said last-named means including a folder and a creaser across the edge of which the folder moves, said creaser having a hole therethrough for the introduction through 10 the creaser and into the fold of a reinforcing element.

23. A machine for folding the margin of sheet material having, in combination, means for bending upwardly the edge of the upper, a folder, a creaser coöperating with the folder to form a crease in the upper, guiding means upon the creaser whereby a reinforcing element may be introduced into the angle of the fold formed by the creaser, and 15 means for applying tension to the cord and for guiding it in the proper relation to the guiding means upon the creaser.

24. In a machine for progressively folding over the cemented margin of a piece of sheet material upon itself, the combination 25 of means for turning up the edge of the material to initiate the fold, means across which the upper is folded to determine the location of the crease, means for slitting the 30 edge of the upper, means for introducing into the crease a flexible filament of reinforcing material, and means for completing the folding of the margin of the material upon itself to inclose said filament and into 35 position to be secured by cement.

25. A machine for folding the margin of a piece of sheet material having, in combination, fold forming means, means for introducing into the fold a reinforcing element, a hammer and an anvil located adjacent to the means for introducing the reinforcing element and coöperating to beat down the folded over portion of the material upon the body portion thereof and 40 upon the interposed reinforcing element, and means for slitting the margin of the material to facilitate the operation of the folding means about concave curves in the 45 edge of the material.

50. 26. A machine of the class described having in combination means for progressively folding over the edge of the piece of shoe material, means for introducing a cord into the fold formed by the folding means, means

for pressing the fold after the fold is completed, and means for moving the pressing means to feed the cord.

27. A machine of the class described having in combination means for progressively folding over the edge of the piece of shoe 60 material, means for introducing a cord into the fold formed by the folding means, means for pressing the fold, and means for moving the pressing means to feed the work and the cord simultaneously.

28. A machine for operating on the uppers of boots and shoes having, in combination, devices for folding the margin of a cemented upper, means for conducting a reinforcing element to the surface of the upper at a fixed distance for the margin to be folded, and a hammer for pressing simultaneously both a portion of the folded margin and a portion of the element upon the body part of the upper.

75 29. A machine for operating on the uppers of boots and shoes having, in combination, an edge turning device, means for guiding a flexible element in a path parallel to the edge, and a hammer constructed and arranged to operate upon the upper at a point where the element lies above the body portion of the upper.

30. A machine for operating on the uppers of boots and shoes having, in combination, devices for folding the margin of a cemented upper including a creaser having a portion for determining the width of the folded margin, and having also a guiding portion for leading a reinforcing element to the upper adjacent to its folded margin.

85 31. A machine for operating upon the margin of a piece of flexible material having, in combination, fold forming and fold pressing mechanism located in such proximity side 90 by side that the margins of pieces of material having sharply curved edges may be operated upon, and means for guiding a reinforcing element in a path parallel to the edge of the material in position to be acted 95 upon by said pressing mechanism.

In testimony whereof I have signed my name to this specification in the presence of two subscribing witnesses.
